UNITED STATES PATENT OFFICE.

WALTER BRUNER, OF BARRY, ILLINOIS.

GATE.

1,066,792.

Specification of Letters Patent.

Patented July 8, 1913.

Application filed September 23, 1912. Serial No. 721,894.

To all whom it may concern:

Be it known that I, WALTER BRUNER, a citizen of the United States, residing at Barry, in the county of Pike and State of Illinois, have invented a new and useful Gate, of which the following is a specification.

The present invention appertains to gates, such as farm gates and the like.

10 It is the object of the present invention to provide novel and improved means for bracing and hanging a gate constructed of spaced rails or slats, in order that the gate will be substantial or rigid and in order that 15 the means for hanging the gate will not be affected by the breaking, injury or sagging of the rails or slats.

15 The present invention also contemplates a gate of the character indicated which shall 20 not only be simple and substantial in construction, but which shall also be comparatively inexpensive and which shall permit the gate to be hung in its median plane and not to one side or the other of the median 25 plane or plane of the rails.

25 To the above and other ends, the present invention resides in the combination and arrangement of parts and in the details of construction hereinafter described and 30 claimed, it being understood that changes in the precise embodiment of invention herein disclosed can be made within the scope of what is claimed without departing from the spirit of the invention.

35 The preferred embodiment of the invention is illustrated in the accompanying drawings, wherein like reference characters have been employed to denote corresponding parts, and wherein:

40 Figure 1 is a side elevation of a gate, partly broken away, constructed in accordance with the present invention. Fig. 2 is a sectional detail taken on the line 2-2 of Fig. 1, on an enlarged scale.

45 Referring in detail to the drawings, the gate embodies in its essentials a plurality of spaced rails or slats 3, which are suitably arranged with respect to each other in order to suit the circumstances, and which may be 50 constructed of any suitable material, preferably wood, and in various dimensions. These rails are secured together by duplicate stiles or uprights 4 arranged at intervals along the rails, and on the opposite faces 55 thereof, the said stiles being constructed of angle iron and bolts or other securing mem-

bers 5 connecting the duplicate stiles, and passing through the rails so as to clamp the rails securely between the stiles.

Duplicate pairs of diagonal braces 6 are 60 arranged on opposite faces of the rails, one of the ends of the braces 6 overlapping the ends of the respective stiles at the hinged end of the rails, and the other ends of the respective braces, being overlapped. These 65 braces 6 are constructed of angle iron and the duplicate braces are connected by bolts or other securing members 5 which also pass through the rails to clamp the rails between the braces. Bolts 7 are engaged through the 70 overlapped ends of the stiles and braces so as to provide rigid and substantial hanger frames at the hinged end of the gate between which the corresponding ends of the 75 rails are engaged. Each of the hanger frames as thus provided is triangular, the two frames being duplicates and each side of each frame being constructed of angle iron having one flange resting against the rails and the said flanges of the respective 80 sides of each frame projecting inwardly relative to the frame.

The triangular hanger frames are adapted to be suspended from a suitable post by means of a pair of hangers 8 fitting between 85 the stiles 4 at the hinged end of the gate, adjacent their ends, and between the respective braces 6, securing members 10 being passed through the said stiles and braces and through the hangers in order to clamp 90 the hangers between the pairs of stiles and braces. Each of the hangers 8 comprises a strap of metal doubled to form an eye 9, the ends of the straps being secured between the respective stiles and braces. The upper 95 and lower hangers 8 abut against the lower and upper edges of the upper and lower rails, respectively, and the said hangers also serve to brace hanger frames, by bracing the upper and lower corners thereof. Thus, 100 the hanger frames, are braced by the hangers 8, the hangers also serving to support the hanger frames in an effective manner.

The hangers 8 are adapted to be engaged to the post by means of a pair of lag screws 105 or other members 11 engaged into the post and having their outer ends upturned to provide pintles 12 over which the eyes of the hangers 8 are adapted to engage. Thus, the gate may be pivoted in its median plane 110 to the post so as to swing with equal ease to either side. It will also be noted that

each rail is independently supported by the hanger frames, and that the rigidity of the hanger frames is not affected by the breaking or injury of any rail. It will be noted 5 that the rails are carried by the hanger frames and that the hanger frames are hinged to the post, so that the rails themselves are not hinged to the post and are relieved of this duty. It will therefore fol- 10 low that the objects aimed at have been carried out in a satisfactory manner, and that the present gate will provide a desirable one for the purposes for which it is designed. Other advantages and capabili- 15 ties of the present invention will be apparent to those versed in the art, and need not be itemized at length.

Having thus described the invention, what is claimed as new is:—

20 A gate embodying spaced rails, duplicate triangular hanger frames on the opposite faces of the rails at the hinged end of the gate, each side of each frame being con-

structed of angle iron having one flange resting against the rails, the said flanges of 25 the respective sides of each frame projecting inwardly relative to the frame and being overlapped at their ends, one side of each frame forming a stile running along the hinged end of the gate, a pair of hangers 30 projecting between certain of the lower and upper rails and fitting between the stiles and the other respective sides of the frames, and securing members connecting the said flanges of the respective duplicate sides of 35 the frames to secure the sides of the respective frames together and to secure the rails and the hangers between the frames.

In testimony that I claim the foregoing as my own, I have hereto affixed my signature in the presence of two witnesses.

WALTER BRUNER.
